UNITED STATES PATENT OFFICE.

LEONARD JOHN KEMP, OF QUEENSTOWN, CAPE PROVINCE, SOUTH AFRICA.

METHOD AND APPARATUS FOR CASTING.

Application filed August 21, 1922. Serial No. 583,279.

To all whom it may concern:

Be it known that I, LEONARD JOHN KEMP, a subject of the King of Great Britain, residing at Queenstown, Cape Province, South Africa, have invented certain new and useful Improvements in Methods and Apparatus for Casting, of which the following is a specification.

This invention relates to casting small objects in a mould, such as fillings for teeth or ornamental goods of metal or porcelain, as for instance a fly, which require very accurate deposit of the molten material in the mould.

The invention further refers to apparatus employed in casting operations of the character referred to.

An object of the invention is to ensure an accurate flow of molten material into the mould so that every crevice is filled.

Another object is to provide a mould ring suitable for holding the compound in which such small objects are moulded, the mould ring being constructed so that it may be temporarily fixed within a furnace and the contents be subjected to pressure during the moulding operation.

A further object of the invention is to construct a furnace adapted to receive a mould for casting small objects, the furnace being constructed so that pressure can be applied to the mould and the molten material, while the latter is heated and during the flow of the "melt".

A still further object is to construct a furnace which is removable from its base plate, the base plate being constructed so that the mould can be fixed thereupon, the arrangement being such that the furnace can be lifted from or placed upon the base plate after the mould has been fixed in position, thereby giving great facility for manipulating the mould and its contents, a further object of the invention being to provide an electrical furnace, the heat from which is controlled by varying the extent of the operative winding of the furnace.

In the accompanying drawings are illustrated some preferred forms of the present invention, in which:

Fig. 1 illustrates diagrammatically in elevation a complete apparatus for carrying out the present invention;

Fig. 2 is a section on the line 2—2 of Fig. 1, to an enlarged scale;

Fig. 3 shows in detail the moulding ring utilized in the construction shown in Figs. 1 and 2; and

Fig. 4 is a section similar to that shown in Fig. 2 through a furnace and moulding ring of modified construction.

Throughout the drawings like reference numerals designate the same or similar parts.

In the construction shown, the pressure applied is a pressure below atmosphere.

Referring now to Figs. 1, 2 and 3 of the drawings, 1 indicates a tank of known form in which a pressure below atmosphere is obtained, 2 being a nozzle connected to the tank and 3 the T piece connected to the nozzle, the T piece being associated with branches 4 and 5, the flow through which is controlled by valves 6, 6, the branch 5 having a socket 7 engaged thereon, the socket 7 being adapted to receive a nipple 8 carried by a circular perforated base plate 9, the base plate 9 being provided with suitable guides 10 for a furnace, the guides being preferably arranged at opposite ends of a diameter. On the base plate 9 is arranged a furnace comprised by a metal cylinder 11, carrying an annulus of refractory material 12, in which is embedded, as indicated at 13, the coils for generating heat by electrical energy. The furnace is arranged vertically and has an opening at the top and at the bottom, the top opening being provided with a removable closure member 14, the furnace being also provided with sockets, preferably of tubular nature as indicated at 15 and formed with the exterior wall 11 of the furnace, through which sockets the guides 10 of the base plate may protrude, the furnace being thereby guided into position on to the base plate, any relative position required being fixed by operating set screws 16 carried in the sockets and adapted to bite into the guides, as will be readily understood. It will be noted that the base plate is a completely separate integer from its furnace, which latter can be entirely removed therefrom, and that the base plate includes the floor of the furnace.

A packing member, such as an annular ring 17 may be arranged, as shown in Fig. 2, between the bottom of the furnace and the base plate 9. Within the furnace is arranged a mould ring 18 carrying investment compound 19, in which may be formed the mould indicated at 20 for a casting operation, the

mould ring 18 being provided with depending arms 21, having hooked extremities 22. The base plate is perforated centrally, as indicated at 23, and at equal distances therefrom, as indicated at 24, through which latter perforations the depending arms 21 of the mould ring 18 protrude.

Around the central perforation 23 and on the base plate 9 is arranged a flexible seating washer 25, on which the mould ring is seated, the arrangement being such that if tension is applied to the arms 21 and considering the base plate 9 to be fixed, an air-tight joint will be obtained between the mould ring and the base plate. In order to apply such tension draw bars 26 are disposed to engage the hooked extremities of the arms 21, the draw bars being connected by a cross bar 27 carrying a threaded member 28 adapted, on being rotated positively, to press against an end of the socket 7, which is recessed as indicated at 29 to receive said threaded member, further rotation of the threaded member results in tension being applied to the draw bars 26 through the medium of the cross bar 27, which is preferably provided with a boss, as indicated at 30, to extend the bearing surface of the threaded member 28.

30 The method of operation considering the apparatus to be used for the manufacture of a filling for teeth, will be as follows:—

A wax impression of the cavity in the tooth will be taken and then placed in a ring mould which will be afterwards packed with an investment compound as is well known in the art. The whole will then be heated to run out the wax and leave a vent, through which molten material may be poured into the mould so formed in the investment compound. The filling material, gold, porcelain, or the like, will then be placed over the vent in the investment compound and the ring mould will be fixed on the base plate 9 so that there is an air-tight joint between them.

The furnace will then be placed in position so that a required heat is obtainable, which will depend upon the material being melted; electrical energy will then be turned on and the moulds of the furnace heated up to melt the casting material, and then connection will be effected between the base of the mould and the vacuum tank, that is, in the case illustrated, the valve 6 will be operated and suction will then occur through the members 2, 3, 5, 7 and 8 and the opening 23 which is connected to the base of the mould; the suction thus applied will cause air to be drawn through the investment compound and as the air is removed from the mould the molten material will flow in and completely fill the cavity formed in the mould, it being understood that as soon as the furnace is placed in position over the

mould, the closure 14 is applied to prevent a draught flowing up through the openings 24 and the interior of the furnace.

In order to vary the extent of the heating surface in the furnace the coils, indicated by the numeral 13, will be connected in series and provided with leads 31, 32, 33, 34; the lead 31 is connected to supply and the leads 32, 33 and 34 are arranged in an arc to be covered at will by a rotatable switch 75 member, diagrammatically illustrated at 35, itself connected to the other terminal of supply.

According, therefore, to which of the leads 32, 33 or 34 that the switch arm 35 engages, so the extent of coils in operation is modified.

A further variation of the current supply to the coils, whatever extent is being used, is obtained by introducing a rheostat, as indicated at 36, on the main, as will be well understood in the art.

Referring now to the modified construction shown in Fig. 4, which is operable to carry out the method of operation described with reference to Figs. 1, 2 and 3, a base plate 37 is provided with an integral nipple 38, and is perforated centrally as indicated at 39, the nipple 38 carrying a threaded sleeve 40 adapted to fit into a socket member such as 7, the member 40 being bored in extension of the opening 39 of the base plate. The base plate is provided with a peripheral flange 41 and carries a flexible ring or washer 42, on which is disposed the furnace, constructed similarly to that already referred to, the furnace being provided with sockets 43 and draw bars 44 associated with threaded members 45 adapted to operate against the base plate 37, which is provided with abutment plates 46 for that purpose. It will be obvious, therefore, that on rotation of the threaded members 45, the furnace will be drawn tightly on to the flexible member 42, thereby obtaining an air-tight joint between the bottom of the furnace and the base plate.

In this construction the refractory material 12 of the furnace is extended to form a bottom to the furnace, the bottom part being perforated, as indicated at 47, in order to provide an opening opposite to the opening 39 of the base plate. On the bottom of the furnace so formed is arranged a flexible washer 48, which forms a seating for the ring mould 49, provided with upwardly extending arms 50, over which engages a cross bar 51, the cross bar being perforated for the reception of draw bars 52 adapted to engage the sockets 43 of the furnace, so that on rotation of the fly nuts 53 of the said draw bars 52, the cross bar 51 is depressed, thereby thrusting down the arms 50 of the ring mould so that the latter is tightly seated on the flexible washer 48, thereby obtaining

an air-tight joint between the ring mould and the bottom of the furnace.

With such a construction it will be obvious that a negative pressure can be applied through the member 40, the opening 39, the opening 47 and to the bottom of the mould, with the resulting withdrawal of the air in the mould, as already explained. The means for regulating the heat of the furnace in this construction may be the same as that already referred to with reference to the construction shown in Fig. 1.

By the present invention completely accurate articles can be cast from porcelain in view of the fact that pressure as well as heat is involved in the operation and that the heat can be closely regulated.

The apparatus is equally useful for casting in metals more easily melted, as for instance gold.

I claim:—

1. In casting apparatus, the combination of a vertical furnace, a base plate for said furnace completely separate therefrom, 25 clamping means for securing said furnace to said base plate, a mould ring, a support therefor, arms on said mould ring, means for applying pressure through said arms to push said mould ring on to its support, and 30 a conduit, through said support, connecting the bottom of said mould to a vacuum tank, whereby air may be withdrawn from the mould as the molten metal flows thereinto.

2. In casting apparatus, the combination 35 of a vertical furnace, a perforated base plate completely separate therefrom and including the floor of the furnace, vertical guides on said base plate for said furnace, a mould ring supported on the base plate, arms extending from said mould ring through said base plate, adjustable means for straining said arms to clamp the mould ring on the base plate, and a conduit, through said base plate, connecting the bottom of the mould 40 to a vacuum tank, whereby air may be withdrawn from the mould as the molten metal flows thereinto.

3. In casting apparatus, the combination 50 of a vertical furnace, a perforated base plate completely separate therefrom and including the floor of the furnace, vertical guides on said base plate for said furnace, means for fixing said furnace in various positions on said guides, a mould ring supported on 55 said base plate, arms extending from said mould ring through said base plate, means connecting said arms to an adjustable ten-

sion member for clamping the mould ring on the base plate, and a conduit, through said base plate, connecting the bottom of 60 said mould to a vacuum tank, whereby air may be withdrawn from the mould as the molten metal flows thereinto.

4. In casting apparatus, the combination 65 of a vertical furnace, a perforated base plate completely separate therefrom, and including the floor of the furnace, vertical guides on said base plate for said furnace, means for fixing said furnace in various positions on said guides, a mould ring supported on 70 said base plate, hooked arms depending from said mould ring through said base plate, a flexible perforated washer interposed between said base plate and the bottom of said mould ring, draw bars engaging 75 the hooked arms, a threaded member, a cross bar on said threaded member, a fixed abutment, said threaded member being rotatable against said fixed abutment to operate the draw bars and clamp the mould ring on the washer, and a conduit, through said base plate and washer, connecting the bottom of 80 the mould to a vacuum tank.

5. In casting apparatus, the combination 85 of a vertical electrical furnace having an opening at the top and at the bottom, a perforated base plate completely separate therefrom including the floor of the furnace and an opening concentric with the opening at the bottom of the furnace, sockets on 90 said furnace and vertical guides on said base plate for said sockets, adjusters fitted to said sockets for fixing the furnace in various positions on said guides, a removable closure for the opening at the top of said furnace, a mould ring supported on the base plate over the opening therein, hooked arms depending from said mould ring through said base plate, a flexible perforated washer interposed between said base plate and the bottom of said mould ring, draw bars engaging 95 the hooked arms, a threaded member, a cross bar on said threaded member, a fixed abutment, said threaded member being rotatable against said fixed abutment to operate the draw bars and clamp the mould ring on the washer, and a conduit, through said base plate and washer connecting the bottom of 100 the mould to a vacuum tank.

6. A mould ring having depending arms, each formed at the free extremity with a hook.

In testimony whereof I affix my signature.
LEONARD JOHN KEMP.
